UNITED STATES PATENT OFFICE.

HENRY P. GEHRICKE, OF LOS ANGELES, CALIFORNIA.

STRAP-LOCK.

SPECIFICATION forming part of Letters Patent No. 665,204, dated January 1, 1901.

Application filed September 29, 1900. Serial No. 31,544. (No model.)

To all whom it may concern:

Be it known that I, HENRY P. GEHRICKE, a citizen of the United States, residing at Los Angeles, in the county of Los Angeles and State of California, have invented new and useful Improvements in Strap-Locks, of which the following is a specification.

My invention relates to devices for locking adjustable straps which are used in pairs, such as the straps which are used on telescopic bags and trunks to hold the parts together; and the object thereof is to provide a locking device whereby such straps may be securely locked upon the bag or other article to which they are usually affixed, and thereby prevent it from being opened without the straps being first unlocked. I accomplish this object by the device described herein and illustrated in the accompanying drawings, forming a part hereof, in which—

Figure 1 is a perspective view of a telescope-bag the retaining-straps on which are locked thereon by my locking device. Fig. 2 is a side elevation of a part of the locking device detached from the bag.

In the drawings, A represents the telescope-bag, whose parts are held securely together by straps B, which are buckled thereon in the usual manner and are securely locked thereon by strap-lock C and padlock I. Strap-lock C is composed of a wire base D, which is bent near each end into a flattened coil E, through which straps B pass to hold them together. The ends are then bent upward and 35 then toward each other to form strap-holding points F. The two wire members G, having eyes H and H' at the ends thereof, are coiled around base D, each of said members G having a single coil around base D near each 40 end thereof, as shown, and having a sliding movement on base D and having each end thereof bent upwardly at substantially right angles to the base and the inner ends thereof projecting past each other and are of such 45 length that when eyes H' are brought together eyes H pass over points F.

In the use of my device straps B are passed through coils E and are then securely buckled on bag A in the usual manner, with coil E 50 near the buckle on strap B. The projecting free ends of straps B are then slipped upon points F. Members G are then moved to

bring eyes H over said points and eyes H' together in the center of the base. The hasp of padlock I is then passed through eyes H' 55 and the padlock is locked in the usual manner, which holds eyes H' together, thereby retaining straps B on points F and preventing their removal from the bag until padlock I is unlocked.

It is obvious that instead of wire being used in the formation of my strap-lock strips of steel or other metal may be used and that coil E may be omitted and other means used for fastening the strap to the base, and the 65 sliding members may be attached to the base in any suitable manner, and I do not restrict myself to the use of wire, my invention being a locking device composed of a base, having strap-retaining points at the ends and means 70 to attach two straps thereto, and two sliding members slidably mounted on said base, whose outer ends are adapted to hold the strap on the strap-retaining points of the base and the inner ends to be locked together to prevent the outer ends from moving, and thereby prevent the straps being removed from the retaining-points of the base.

Having described my invention, what I claim as new, and desire to secure by Letters 80 Patent, is—

1. A strap-lock, comprising a base having catches on each end thereof for holding the free end of a strap, the projecting ends of said catches adapted to enter an opening on 85 sliding members in said base, to prevent the removal of the straps from the catches while the sliding members are in their extended or locking position, and to prevent their removal in their closed, or unlocked, position; 90 two sliding members on said base having on their ends, apertures adapted to receive, on their outer ends, the projecting end of the catch when in its extended or locking position; the apertures on the inner end of said 95 sliding members adapted to receive the hasp of a padlock in the locking position, substantially as shown and described.

2. The combination of two straps, adapted to be buckled upon a bag, with a locking device composed of a base, having catches at the ends thereof; two sliding members on said base, having upturned ends, the inner ends adapted to be locked together, and the

outer ends to fasten the ends of the straps on the catches of the base.

3. A strap-lock, comprising a wire base, the said wire base being bent at the ends, as shown, to form a loop to receive the binding-
straps; sliding wires bent around the base-
wire, as shown, and adapted to move longitudinally on said base-wire, the said sliding
wires being bent at both ends, one end forming a loop to receive the inwardly-projecting

ends of the base-wire, and the other bent into a loop to receive the hasp of a lock, substantially as shown and described.

In witness that I claim the foregoing I have hereunto subscribed my name, this 22d day of September, 1900, at Los Angeles, California.

H. P. GEHRICKE.
